UNITED STATES PATENT OFFICE

1,974,269

WINDOW

Edward L. Gonner, North Canton, Ohio

Original application May 1, 1930, Serial No. 448,903, now Patent No. 1,856,158, dated May 3, 1932. Divided and this application May 2, 1932, Serial No. 608,756

2 Claims. (Cl. 189—76)

My invention relates to windows, including sashes and frames in which the sashes are operatively mounted, and more particularly to metal windows, and to windows of the type known as double hung windows; and the present improvements are a division of the improvements set forth in my prior application for United States Letters Patent for Windows, Serial No. 448,903, filed May 1, 1930, and allowed March 3, 1932, and upon which United States Letters Patent No. 1,856,158, dated May 3, 1932, has been issued.

Due to the growing scarcity of lumber, and also due to the imperfect drying of ordinary commercial lumber, windows made of wood are becoming more and more unsatisfactory from the standpoint of tightness and ease of operation.

Metal windows have been made from rolled steel sections, but most of such metal windows are of the type known as casement windows, that is, windows including swinging sections instead of sliding sashes.

Many builders and building owners prefer the double hung type of windows, that is to say windows including upper and lower sashes sliding up and down in frames.

No satisfactory metal window of this type is at present available, it having been found to be very difficult to make the sashes slide easily, and to make the windows weather tight, in the double hung metal windows heretofore available. Moreover such double hung metal windows have been relatively expensive.

The objects of the present improvements include the provision of a novel window sash, preferably for use in a double hung window and the like which may include a frame and upper and lower sashes of the present improvements slideable in the frame, and one of the sashes in a certain position with respect to the other being pivotal about a horizontal axis in either direction, and the improved sash being adapted for very economical production by the use of relatively light gauge sheet metal, and the sash being arranged for removably mounting its glass pane.

These and other objects are attained by the structures, apparatus, parts, improvements, and combinations, which comprise the present invention, and which are particularly and distinctly pointed out and set forth in the appended claims forming part hereof.

In general terms the improved window of my aforesaid prior application of which this application is a division, includes a plurality of

members each preferably made of formed relatively light gauge sheet metal, and some of the members being included in a frame and others of the members being included, respectively, in upper and lower sashes each including the present improvements and each slideable up and down in a set of opposite grooves formed in the frame side members, and the window including cooperating means for sliding the sashes from a normal closing position in the frame opening to another position in which one of the sashes may be pivoted around a horizontal axis in either direction independently of the other.

In general terms each of the improved sashes may be described as including a lower transversely extending tubular cross member secured at its outer ends as by welding to the lower ends of preferably tubular side members, and the upper ends of the side members are secured as by welding to the outer ends of an upper preferably tubular cross member.

The upper surface of the lower cross member has formed therein an upwardly opening transversely extending groove for receiving the lower end of a glass pane, and the side edges of the glass pane fit in opposite opening grooves formed in the opposite inner faces of the side members.

In order to eliminate the use of putty in setting the glass pane in the sash, the upper cross member includes an upwardly opening channel member having a lower web provided with a transversely extending slot.

At the front and rear sides of the web, outside and inside flanges extend upwardly and transversely, and a transversely and downwardly extending fold rib is formed on the upper transversely extending side of each flange.

A closure member is longitudinally slidably engaged with the fold ribs of the flanges, so that the closure member may be applied to or removed from the slotted channel cross member.

The glass pane is inserted into the sash by sliding it downwardly through the slot in the channel cross member, and is retained in the sash when the closure member is applied to the slotted channel cross member, preferably in stopping abutment with the upper end of the glass pane.

A preferred embodiment of a window including the improvements is illustrated in the accompanying drawings forming part hereof, in which

Figure 1 is an elevation view looking from the normally inside of the window with portions broken away to illustrate details of construction and arrangement;

- Fig. 2, a sectional view thereof as on line 2—2, Fig. 1, the dot-dash lines illustrating the sashes of the window when rotated about their horizontal pivots from their normal closing position;
- 5 Fig. 3, a view similar to Fig. 2 illustrating the normally lower sash raised to an upper position, and the normally upper sash lowered to a lower position from which both sides of the window pane of the normally upper sash may be easily 80 washed by rotating the sash successively inwardly and outwardly to or beyond the positions illustrated by the dot-dash lines;
- 10 Fig. 4, a fragmentary transverse sectional view of the improved window as on line 4—4, Fig. 1;
- 15 Fig. 5, another fragmentary transverse sectional view as on line 5—5, Fig. 1;
- 20 Fig. 6, a view similar to Fig. 4 illustrating one of the guide rails for the normally upper sash in the position permitting rotation of the sash about its pivotal mounting;
- 25 Fig. 7, an enlarged fragmentary detached oblique perspective view illustrating improved details of construction of one of the sashes of the present improvements;
- 30 Fig. 8, a view similar to Fig. 7 with the closure member of the sash removed;
- 35 Fig. 9, a fragmentary detached oblique perspective view similar to Figs. 7 and 8 illustrating the closure member of Fig. 7, which has been removed from the parts illustrated in Fig. 8;
- 40 Fig. 10, an enlarged fragmentary transverse sectional view of one of the improved sashes, removed from the window; and
- 45 Fig. 11, an enlarged vertical sectional view illustrating the lower sash swung to a position permitting changing of the glass pane thereof from the inside.
- 50 Similar numerals refer to similar parts throughout the several views.
- 55 The improved window indicated generally at 10, includes in combination with other parts, a plurality of members each preferably made of relatively light gauge formed sheet metal.
- 60 Some of the formed members are included in a frame indicated generally at 11; and others of the formed members are included in an upper sash indicated generally at 12, and in a lower sash indicated generally at 13, each of the sashes being slidable up and down in the frame independently of the other, and each sash being mounted in a novel manner for rotation about a horizontal axis, as is hereinafter set forth in detail.
- 65 The frame 11 includes a lower transversely extending preferably tubular cross member indicated generally at 14 which is secured at its outer ends as by welding to the lower ends of preferably tubular side members indicated generally at 15 and 15', and the upper ends of the side members 15 and 15' are secured as by welding to an upper preferably tubular cross member indicated generally at 16.
- 70 All of the tubular frame members are preferably formed of sheet material.
- 75 The lower tubular cross member 14 includes a transversely extending formed channel member indicated generally at 17.
- 80 The channel member 17 preferably includes a transversely extending formed and sloping web 17a having at the inside thereof and angular thereto a downwardly depending transversely extending preferably vertical flange 17b, and having at the outside thereof and angular thereto a downwardly depending transversely extending preferably vertical flange 17c.
- 85 The lower transversely extending side of the flange 17b has preferably formed thereon a transversely and inwardly extending securing rib 17b'; and the lower transversely extending side of the flange 17c has preferably formed thereon a transversely and inwardly extending securing rib 17c'.
- 90 A base plate 18 is secured at its sides as by welding, not shown, to the securing ribs 17b' and 17c' for completing the tubular cross member 14.
- 95 For providing a weather-tight closure between the frame and the lower sash, the inner transversely extending side of the web 17a is preferably provided with an upwardly protruding rib 17d, and the web 17a slopes downwardly and outwardly from the base of the rib 17d.
- 100 The frame 11 also includes as aforesaid preferably tubular grooved side members 15 and 15', the side member 15 being at the left, and the side member 15' being at the right, as illustrated in Fig. 1.
- 105 Each grooved tubular side member is similarly constructed with the exception that the grooves of one open towards the grooves of the other, and consequently are formed in relatively opposite faces of the transversely spaced side members.
- 110 The tubular side member 15 includes a normally vertically extending formed channel member indicated generally at 19.
- 115 The channel member 19 preferably includes a normally vertically extending web 19a having at the outside thereof and angular thereto an outwardly and normally vertically extending flange 19b, and having at the inside thereof and angular thereto an outwardly and normally vertically extending flange 19c.
- 120 The outer normally vertically extending side of the flange 19b has preferably formed thereon a securing rib 19b' extending normally vertically and towards the flange 19c; and the outer normally vertically extending side of the flange 19c has preferably formed thereon a securing rib 19c' extending normally vertically and towards the flange 19b.
- 125 An outer closure plate 20 is secured at its sides as by welding, not shown, to the securing ribs 19b' and 19c' for completing the tubular side member 19.
- 130 The web 19a has formed therein parallel and normally vertically extending spaced grooves 19e and 19f.
- 135 The side member 15' is similar in construction and includes a channel member indicated generally at 19' secured to a closure member 20'; and the outer face of the channel member 19' has spaced parallel grooves formed therein, and opposite to and opening towards the openings of the grooves 19e and 19f.
- 140 The upper tubular cross member 16 includes a transversely extending formed channel member indicated generally at 21.
- 145 The channel member 21 preferably includes a transversely extending formed web 22a having at the inside thereof and angular thereto an upwardly and transversely extending normally vertical flange 22b, the flange 22b being located intermediate the inside and outside of the frame, and the web 22a having at the outside thereof and angular thereto an upwardly and transversely extending normally vertical flange 22c.
- 150 The upper transversely extending side of the flange 22b has preferably formed thereon a securing rib 22b' extending transversely and away from the flange 22c; and the upper transversely extending side of the flange 22c has preferably 150

formed thereon a securing rib 22c' extending transversely and towards the web 22b.

A top closure plate 23 is secured at its sides as by welding, not shown, to the securing ribs 5 22b' and 22c' for completing the tubular cross member 16.

For providing a weather-tight closure between the frame and the upper sash the outer transversely extending side of the web 22a is preferably provided with a downwardly protruding rib 22d; and the web 22a is thus upwardly offset from the lower edge of the rib 22d and the rib 22b' is upwardly offset from the web 22a.

The normally upper sash 12 is slideable up and 15 down in the groove 19f of the side member 19 and in the opposite groove of the side member 19'.

The normally lower sash 13 is slideable up and down in the groove 19e of the side member 19 and in the opposite groove of the side member 19'.

20 Each sash is similar in details of construction, and includes a lower transversely extending tubular cross member indicated generally at 24 which is secured at its outer ends as by welding to the lower ends of preferably tubular side members indicated generally at 25 and 25', and the upper ends of the side members 25 and 25' are secured as by welding to the outer ends of an upper preferably tubular cross member indicated generally at 26.

30 The upper surface of the cross member 24 has formed therein an upwardly opening transversely extending groove for receiving the lower end of a glass pane 27, and the side edges of the glass pane 27 fit in oppositely opening grooves formed 35 in the opposite inner faces of the side members, as indicated for example at 28 in the side member 25.

For facilitating production of the sashes by 40 eliminating setting of the glass panes therein by the use of putty, each upper sash member 26 includes an upwardly opening channel member 29, comprising a unitary sheet metal piece, and the channel member 29 includes a web 29a in which a transversely extending slot 29a' is formed, and 45 at the front and rear sides of the web 29a outside and inside flanges 29b and 29c, respectively, extend upwardly and transversely.

The upper transversely extending side of the flange 29b has preferably formed thereon a 50 transversely and downwardly extending folded rib 29b' and the upper transversely extending side of the flange 29c has preferably formed thereon a transversely and downwardly extending folded rib 29c'.

55 A closure member indicated generally by 30 includes a web 30a, and at the front and rear sides of the web 30a outside and inside flanges 30b and 30c, respectively, extend downwardly and transversely.

60 The lower transversely extending side of the flange 30b has preferably formed thereon a transversely and upwardly extending folded rib 30b' and the lower transversely extending side of the flange 30c has preferably formed thereon a transversely and upwardly extending folded rib 30c'.

The downwardly extending folded rib 29b' of the channel member 29 interfits between the flange 30b and the upwardly extending folded rib 70 30b' of the closure member, and the upwardly extending folded rib 30b' interfits between the downwardly extending folded rib 29b' and the flange 29b' of the channel member 29.

Similarly, the downwardly extending folded 75 rib 29c' of the channel member 29 interfits be-

tween the flange 30c and the upwardly extending folded rib 30c' of the closure member, and the upwardly extending folded rib 30c' interfits between the downwardly extending folded rib 29c' and the flange 29c of the channel member 29.

80

With this construction the members 29 and 30 are interlocked to form the separable glass receiving tubular member 26, for the purpose of providing an easy method of assembling the pane 27 in the sash 12 by first entering the pane 27 in the slot 29a' of the channel member 29, and then longitudinally sliding the closure member 30 into interlocking engagement with the channel member 29, as shown in Fig. 7.

85

The side sash member 25 includes vertically extending side flanges 31a and 31b, as best shown in Figs. 4, 5, and 6, and the vertically extending web member 32 extending transversely between the inner ends thereof. The outer ends of the side flanges 31a and 31b are inturned to form transversely and vertically extending flanges 33a and 33b which slidably engage the face 19a of the side frame immediately adjacent the sides of the vertically extending groove 19f. Vertically extending flanges 34a and 34b extend inwardly from the ends of flanges 33a and 33b, respectively, and parallel with side flanges 31a and 31b, respectively, of the tubular member 25.

95

The flanges 34a and 34b are inturned at their inner ends to form vertically and transversely extending flanges 35a and 35b, respectively, the inner ends of which are spaced apart to form a vertically extending groove 36.

105

A vertically extending plate 37 is secured to the inside faces of the flanges 35a and 35b to 110 form a closure for the slot 36.

The side flanges 34a and 34b form, with the inturned flanges 35a and 35b, and the closure plate 37, a vertically extending channel within the tubular side sash member 25, and adjacent 115 to and registering with the vertically extending groove 19f in the side frame.

A vertically extending tubular sash guiding member 38 is normally slidably mounted in the groove 19f and extends inwardly to slidably engage the inner faces of side flanges 34a and 34b.

120

Means for laterally moving the sash guiding member 38 inwardly out of engagement with the groove 19 and into the position shown in Fig. 6, preferably includes laterally extending rods 125 39 positioned near the top and bottom of the side member 25. Each rod 39 may be screwed into the guiding member 38 as at 40, and extends inwardly respectively through an aperture provided in the closure member 37, slot 36, and 130 through an aperture provided in the web 32. A collar 41 is formed upon each rod 39 to abut the inner face of the web member 32 when the guiding member 38 is in engagement with the groove 19f, and the inner end of the rod has a knob 42 135 secured thereon and spaced from the collar 41.

A hook 43 is pivotally mounted at one of its ends on the side sash member 25 as at 44, adjacent each rod 39, and is arranged to engage each rod between the collar 41 and the knob 42 for 140 normally holding the sash guiding member 38 in engagement with the groove 19f in the position shown in Fig. 4.

The tubular side sash member 25' is similar in 145 details of construction to member 25, and includes a sash guiding member 38' normally slidably engaging the side frame member 15', and is provided at its top and bottom portions with a rod 39' for laterally moving the guiding member 38' into and out of engagement with the side 150

sash member 25', and is also provided with hooks 43' normally engaging the rods 39'.

The sash 12 is pivotally mounted at the central portions of the side sash members 25 and 25' as by pivot pins 45 and 45', respectively, upon the side frame members 15 and 15', respectively, for rotation about the horizontal axis determined by pivots 45 and 45'.

As best shown in Fig. 5, the pivot pin 45 has a knob upon its inner end normally engaging the inner flange 32 of the side sash member 25, and the pivot pin 45 extends therefrom respectively through an aperture provided in the flange 32, thence through slot 36, an aperture provided in closure member 37, guide member 38, an aperture 138 in groove 19f, and thence into sliding engagement with the walls of a tubular member 46 secured to the closure plate 20 of the side frame member 15.

A collar 47 is secured to the pin 45 adjacent the slot 36, and a compression spring 48, interposed between the collar 47 and the flange 32 normally holds the collar 47 within the slot and in abutment with the slot closure plate 37, in the position shown in Fig. 5, with the pin 45 extending into the tubular member 46.

Similarly, the pivot pin 45' is held in pivotal engagement with the side frame member 15'.

The lower sash 13 is similarly mounted within the frame 11, and includes an upper cross member 26a and a lower cross member 24a, and is provided with sash guide operating rods 39a and 39a', and sash pivot pins 45a and 45a'.

The lower sash 13 is preferably of somewhat greater height than the upper sash 12, and its upper cross member 26a is immediately horizontally adjacent to the lower cross member 24 of sash 12, when the sashes are in their normally closed position shown in Figs. 1 and 2.

In this position, the guiding means of the lower sash 13 slidably engage the groove 19e and the guiding means of the upper sash 12 slidably engage the groove 19f, and the upper cross member 26 of the upper sash 12 abuts the offset portion 22a of the upper frame cross member 16.

If it is desired to rotate the sashes without changing their relative vertical positions, a person standing upon the inside of the window may release the hooks 43 and 43' from engagement with the rods 39 and 39', when the sash 12 may be swung top inwardly in a manner indicated by the dotted line position in Fig. 2, until the lower cross member 24 abuts the lower edge of the rib 22d upon the top frame member 16.

Similarly, the lower sash 13 may be swung top inwardly in a manner indicated by the dotted line position indicated in Fig. 2, until its upper cross member 26a abuts the upper edge of the rib 17d of the frame member 14.

For the purpose of making all portions of the upper sash more easily accessible, as for instance to a person standing inside the window without the person having to stand upon a stool or ladder and the like, the sashes may be moved vertically relatively to each other, to the position shown in Fig. 3, in which position the upper cross member 26a of the lower sash 13 abuts the flange 22b' of the upper frame member 16, and the lower cross member 24 of the upper sash abuts the sill member 14 of the frame.

To raise the lower sash, the operator grasps the knobs of the pins 45a and 45a' and pulls them inwardly toward each other, thereby withdrawing the pins from engagement with tubular

members mounted on the frame and corresponding to member 46 of Fig. 5.

While holding the pins in this position, the operator pushes the sash upwardly until the position shown in Fig. 3 is reached, whereupon he releases the pins 45a and 45a'.

A tubular member 49 similar to member 46 is secured to the side frame 15 and axially aligned with an aperture 50 formed in the groove 19e adjacent the aperture 138 in the groove 19f, and the aperture 50 is positioned so as to register with the pin 45a when the sash 13 is in the raised position shown in Fig. 3.

Similarly, an aperture and tubular member axially aligned therewith is positioned upon the side frame member 15' for the purpose of registering with the pin 45a'. Thus when the operator releases the pins 45a and 45a' with the sash in raised position, the sash will be pivotally mounted in that position upon the side frames 15 and 15'.

In like manner a tubular member similar to member 46 is secured to the side frame 15 and axially aligned with an aperture 138a formed in the groove 19f adjacent to the aperture in the groove 19e which receives the pin 45a, and positioned so as to register with the pin 45 when the sash is lowered to the position shown in Fig. 3.

Similarly a tubular member axially aligned with an aperture in the frame 15' is positioned so as to register with the pin 45'. Thus the sash 12 is pivotally mounted in its lowermost position by the pins 45 and 45' upon the side frames 15 and 15', respectively.

The sash 12 may be lowered in the same manner as the sash 13 is raised, as above described, and when the sash 12 is in its lowermost position, it may be rotated in either direction as shown by the dotted line positions in Fig. 3, 115 so that all portions of the sash may be easily accessible to a person standing on the floor.

I claim:

1. In a metal window, a sash including side members and transversely extending cross members, one of the cross members comprising a unitary sheet metal piece having a transversely extending slot formed therein and a transversely extending folded rib at each side of the slot, and the other cross member and the side members each having a continuous groove formed therein, the grooves communicating with each other and with the slot, a glass pane located in the grooves and slot, and a retaining member including folded ribs interfitting with the folded ribs of the slotted cross member.

2. In a metal window, a sash including side members and transversely extending cross members, one of the cross members including a transversely extending sheet metal channel having a web and a flange at each transverse edge of the web, the web having a transversely extending slot formed therein and each flange having a transversely extending folded rib at each outer edge thereof, and the other cross member and the side members each having a continuous groove formed therein, the grooves communicating with each other and with the slot, a glass pane located in the grooves and slot, and a retaining channel including a web having a flange at each side edge and a folded rib at the outer edge of each flange, the retaining channel folded ribs interfitting with the slotted channel folded ribs.

EDWARD L. GONDER.
